UNITED STATES PATENT OFFICE.

CHARLES M. BRADFORD, OF BOSTON, AND RALPH C. SIMMONS, OF BEVERLY, MASSACHUSETTS, ASSIGNORS TO UNITED SHOE MACHINERY CORPORATION, OF PATERSON, NEW JERSEY, A CORPORATION OF NEW JERSEY.

SHOE-SHAPING MACHINE.

Original application filed August 24, 1916, Serial No. 116,676. Patent No. 1,331,613, dated February 24, 1920. Divided and this application filed November 29, 1918. Serial No. 264,641.

To all whom it may concern:

Be it known that we, CHARLES M. BRADFORD and RALPH C. SIMMONS, citizens of the United States, residing at Boston, in the 5 county of Suffolk and State of Massachusetts, and Beverly, in the county of Essex and State of Massachusetts, respectively, have invented certain Improvements in Shoe-Shaping Machines, of which the following description, in connection with the accompanying drawings, is a specification, like reference characters on the drawings indicating like parts in the several figures.

This invention relates to machines for use 15 in the manufacture of shoes for shaping the shoe on its last, this application being a division of our application which resulted in United States Letters Patent No. 1,331,613 granted February 24, 1920. Since the necessity for the use of machines of the type to which the invention relates arises particularly in the manufacture of turn shoes, the invention will be herein described with particular reference to such use, but it will be 20 understood that the invention is not limited in utility to the manufacture of this particular type of shoe.

After a shoe of the above-mentioned type has been turned and mounted on a last it 30 must be operated upon in various ways in order to shape it properly to the last and thus to insure a comfortable fit and a shapely appearance in the finished shoe. Operations with this end in view usually include 35 a beating and an ironing of the upper round the toe and along the sides of the shoe, including the parts of the upper in and adjacent to the crease between the upper and the sole, in order to eliminate wrinkles and 40 shape the upper smoothly to the last. A frequent result of this treatment of the upper is the opening or widening of the crease between the upper and the sole by reason of the downward bending of the margin of the 45 sole through the action of the beating or ironing tool during its operation on the upper. In order to correct this condition the sole likewise must be subjected to treatment, the operations on the sole having also in 50 view the flattening of any ridge which there may be where the upper attaching seam is located and the shaping of portions of the sole, particularly in the shank, to the lat-

erally convex curvature of the bottom of the last.

This invention provides improved means for shaping a shoe on its last, the construction shown being particularly designed for use in shaping the sole. A feature of the invention consists in a novel construction 60 and arrangement including a tool mounted for reciprocatory movement along the surface of a shoe and operating means designed to facilitate the presentation of the work to the tool and the manipulation of the work to 65 secure the desired results on the particular portions requiring treatment. The construction shown comprises a tool which is mounted to reciprocate in a path inclined to the vertical in such relation to the operator's 70 working position as to permit the shoe in the hands of the operator to be held against the tool with upwardly and backwardly directed pressure. This construction has the advantage of affording the operator a view 75 of the portion of the work under treatment while permitting the work to be handled and manipulated as desired without undue effort or inconvenience.

The above and other features of the invention, including improved operating means for the tool and certain details of construction and combinations of parts, will now be described with reference to the accompanying drawings and pointed out in the 85 claims.

In the drawings:

Figure 1 is a view in front elevation of the head portion of a machine including an embodiment of this invention;

Fig. 2 is a view of the same parts in side elevation, and

Fig. 3 is a plan view of a portion of the machine with a part of the casing broken away to reveal the interior construction.

The drawings illustrate the invention as embodied in a machine of the character disclosed in our above mentioned patent of which this is a division, including among other features means for performing a shaping operation upon the upper of the shoe, but it will be understood that such illustration is merely for convenience and not intended to impose any restriction upon the scope or utility of the invention. The machine comprises a base casting 2 from which

extends a bracket 4 supporting at its outer end a horizontal shaft 6 which is driven by means of a belt 8 from a main operating shaft 10. As shown in Figs. 2 and 3, the bracket 4 at its outer end is curved forwardly toward the operator's working position and supports a pivot rod 12 extending substantially at right angles to the shaft 6 and upon which is mounted for oscillatory movement a tool support in the shape of a bell crank with one arm 14 extending substantially horizontally toward the end of the shaft 6 and the other arm 16 extending diagonally forward and downward. Secured in any suitable way to the arm 16 is a tool 18 which may be constructed of metal or of other material suitable for the purpose in view, the tool being elongated in a substantially horizontal direction and presenting a comparatively narrow working face concavely curved transversely of the path of movement of the tool. For imparting oscillatory movement to the tool 18 the shaft 6 is provided at its front end with a crank disk 20 which carries a crank pin 22 the projecting end of which is journaled in a block 24 having trunnions 26 mounted to slide endwise and to rock in bearings in spaced confronting portions of the arm 14. As the shaft 6 is rotated and carries the crank pin 22 around in a circular path, oscillatory movement is imparted by the crank pin to the tool support 14, 16, the block 24 sliding from side to side on its trunnions 26 as required to accommodate itself to the different positions of the crank pin, while maintaining a continuously operative connection between the shaft 6 and the tool. In order to permit the extent of the movement of the tool to be varied at will, the crank pin 22 is mounted eccentrically upon a stud 28 which is positioned eccentrically in the crank disk 20 and is rotatable to position the crank pin at different distances from the center of the disk. The stud 28 is secured in adjusted position by means of a clamping bolt 30.

In the operation of the machine the tool 18 is rapidly oscillated in the manner above explained in a path which is inclined downwardly from front to rear, permitting a shoe in the hands of the operator to be presented in an inclined position, as shown in Fig. 2, and held against the tool with pressure directed diagonally upward and backward. As thus presented the portion of the shoe under treatment is within view of the operator to enable him readily to observe the progress of the operation of the tool upon the shoe, the relation of the path of movement of the tool to the operator's working position enabling him conveniently to hold the shoe in contact with the tool under the required pressure and to manipulate the shoe as necessary for shaping the different portions of the sole. The concave curvature

of the working face of the tool, arranged to extend laterally across the shoe, is of particular utility in operating along the margin of the sole to bend its edge toward the upper for closing the crease adjacent to the upper and also in pressing down that part of the sole in which the seam is located and imparting to the sole, particularly in the shank, the lateral convex curvature which is desired for the finished shoe. 75

While the tool 18 is herein illustrated as a rubbing tool, it should be understood that the invention in its broader aspects is not limited to a construction in which the tool engages the work frictionally. 80

Having described the invention, what we claim as new and desire to secure by Letters Patent of the United States is:

1. In a machine of the class described, a non-rotary tool for shaping the sole of a shoe by rubbing movement along the surface of the sole, and means for imparting simple oscillatory movement to the tool, the tool being arranged to receive the upwardly directed pressure of a shoe in the hands of the operator. 85

2. In a machine of the class described, a tool for shaping the sole of a shoe by rubbing movement along the surface of the sole, the tool being arranged to receive the upwardly directed pressure of a shoe in the hands of the operator, and means for oscillating said tool lengthwise of the shoe about a single axis. 95

3. In a machine of the class described, a tool for shaping the sole of a shoe by rubbing pressure, said tool extending substantially horizontally, and means for oscillating the tool continuously about a single substantially horizontal axis during the operation of the machine, the tool being arranged to operate by movements lengthwise of a shoe presented thereto in the hands of the operator. 100

4. In a machine of the class described, a tool for shaping the sole of a shoe by rubbing pressure, said tool being concavely curved for transverse engagement with the bottom surface of the margin of the sole, and means for oscillating said tool, the tool being arranged to operate upon a shoe presented thereto in the hands of the operator. 110

5. In a machine of the class described, a tool for operating upon the sole of a shoe by movement along the bottom surface of the sole, said tool being mounted for simple oscillatory movement toward and from the operator in a path inclined downwardly from front to rear and arranged to operate upon a shoe presented by the operator bottom upward and held against the tool with pressure directed diagonally upward and backward, and means for operating the tool. 120

6. In a machine of the class described, a tool for shaping the sole of a shoe by rub- 130

- bing pressure applied progressively along the bottom surface of the sole, said tool being mounted to oscillate about a single axis in a path inclined downwardly from front to rear and constructed to present a shoe engaging surface facing diagonally forward and downward for engagement with a shoe in the hands of the operator, and means for operating the tool.
- 10 7. In a machine of the class described, a tool for shaping the sole of a shoe by pressure applied progressively along the bottom surface of the sole, said tool being mounted for reciprocatory movement lengthwise of a shoe presented thereto in the hands of the operator and constructed to present a shoe engaging face concavely curved laterally of the shoe, and means for operating the tool.
- 15 8. In a machine of the class described, a tool for shaping the sole of a shoe by pressure applied progressively along the surface of the sole, said tool being mounted for oscillatory movement in a path inclined downwardly from front to rear and arranged to operate upon a shoe held against it by the operator with upwardly and backwardly directed pressure, the tool being constructed to present a shoe engaging face concavely curved laterally of the shoe, and means for operating the tool.
- 20 9. In a machine of the class described, a tool for shaping the sole of a shoe by pressure applied progressively along the bottom surface of the sole, said tool being mounted for simple oscillatory movement lengthwise of a shoe presented thereto in the hands of the operator, means for operating the tool, and means for varying the extent of the movement of the tool.
- 25 10. A machine of the character described, comprising a shoe-engaging tool and a holder therefor arranged to execute oscillatory motion about an axis, an operating eccentric arranged to revolve about an axis substantially transverse to that of the tool-holder, and a member constructed and arranged to couple said eccentric and the tool-holder so as to transmit motion from the former to the latter, said member being movable relatively to the tool-holder in lines parallel to the axis of the latter and being movable lengthwise of and relatively to the eccentric to assimilate the angular movement of the tool-holder.
- 30 11. A machine of the character described, comprising a shoe-engaging tool and a holder therefor arranged to execute oscillatory motion about an axis, an operating shaft arranged to rotate about an axis substan-
- tially transverse to that of the tool-holder, 60 an eccentric carried by the shaft, and a member constructed and arranged to couple the eccentric and the tool-holder so as to transmit the eccentric motion to the latter, said member being movable relatively to the tool-holder in lines parallel to the axis thereof and being movable relatively to the shaft in lines parallel to the shaft-axis to assimilate the angular movement of the tool-holder without moving the shaft endwise. 70
12. In a machine of the class described, the combination with a shoe shaping tool, of a support for said tool mounted for oscillatory movement, an operating shaft extending in transverse relation to the axis of 75 oscillation of said support, and means for transforming rotary movement of said shaft into oscillatory movement of the tool support comprising a block slidably mounted on said support and a crank pin on the 80 shaft journaled in said block, said crank pin being adjustable to vary the extent of oscillation of the tool support.
13. A machine of the character described, comprising a shoe-engaging tool and a holder therefor arranged to execute oscillatory motion about an axis, said holder having spaced confronting portions, a member arranged between and pivotally connected to said confronting portions so as to be movable relatively thereto along lines parallel to the axis of the tool-holder, and an operating eccentric engaging said member, between said confronting portions and arranged to revolve about an axis transverse to that of 95 the tool-holder, said member being movable relatively to the eccentric lengthwise of the latter so as to assimilate the angular movement of the tool-holder. 90
14. In a machine of the class described, a 100 tool for shaping the sole of a shoe by movement along the surface of the sole, said tool being constructed and arranged to operate upon a shoe presented thereto in the hand of the operator, and means for imparting to 105 said tool reciprocatory movements in a path inclined to the horizontal and in such relation to the operator's working position as to permit an operator to press the shoe diagonally upward and backward against the tool. 110
- In testimony whereof I, the said CHARLES M. BRADFORD, have signed my name to this specification.
- CHARLES M. BRADFORD.
- In testimony whereof I, the said RALPH C. 115 SIMMONS, have signed my name to this specification.
- RALPH C. SIMMONS.
